NORMAN H. SAUNDERS, OF HOMEWOOD, ILLINOIS, ASSIGNOR TO RESERVE HOLDING COMPANY, OF KANSAS CITY, MISSOURI, A CORPORATION OF DELAWARE.

AUTOMATIC TELEPHONE SYSTEM.

Application filed March 31, 1927. Serial No. 179,782.

The present invention relates to automatic telephone systems in general, but is concerned more particularly with automatic telephone systems containing subscribers' 5 lines of different characters. The invention is furthermore concerned especially with telephone systems in which almost all the lines are of one character, while only a very small number of the lines are of another 10 character.

In explanation of the foregoing, it may be pointed out that it has become standard practice in automatic telephone exchanges wherein the switches are operated in accordance with the so-called two-wire control circuit to arrange all lines that are of a relatively short length for loop operation in controlling the automatic switches, and to arrange the longer lines, for example those 15 extending into the rural territories for controlling the automatic switches over a so-called simplex circuit (two sides of the line in parallel and a ground return). It has become standard practice in telephone exchanges 20 wherein there are only a few rural lines, say a dozen or less, to provide each rural line with a simplex-to-loop repeater individual thereto between the line and its individual line switch. When this is done, 25 the exchange switches may be all of standard loop type.

Another problem involved in the foregoing situation is the provision of arrangements for signalling the various stations on 30 the simplex rural lines, as these lines are practically always party lines, the ringers being operated according to predetermined 35 codes to signal the various stations.

It is an object of the present invention to 40 provide a code selector individual to each party line arranged to respond to the operation of the calling device on a calling line after a connection has been extended to the called line to select the particular code necessary 45 to signal the called station.

It is a further object of the invention to combine this code selector with the individual line repeater in such a manner as to reduce the required equipment.

50 A further object of the invention is to provide suitable circuit arrangements whereby the code selector may be set by impulses

transmitted over a non-talking conductor from a calling connector after the connector has seized the line. 55

A further object of the invention is to provide suitable circuit arrangements whereby a connector of the so-called rotary type, having a fourth wiper used as a rotary test wiper, may be arranged so that the same 60 fourth wiper is utilized for the transmission of impulses to set the code selector.

A still further object of the invention is the provision of suitable arrangements for maintaining a line busy after the calling 65 connector has released until the code selector has returned to its normal position.

A still further object of the invention is the provision of suitable arrangements so 70 that the ringing current ordinarily transmitted by the connector is not effective in reaching the called line so as to avoid a confusion of ringing signals.

A feature of the arrangement is that the contacts in the combined repeater and code 75 selector that are used for repeating impulses when a call is made from a party line are employed to prevent ringing current sent out by a connector from reaching the called party line. 80

The foregoing objects and features, together with others which are more or less incidental, may be understood best after the following description has been considered in connection with the accompanying drawings 85 comprising Figs. 1 and 2.

Referring now to the drawings, they show by means of the usual circuit diagrams a sufficient amount of apparatus in a telephone system embodying the features of the invention to enable the invention to be understood. 90

Fig. 1 shows a connector arranged to be operated according to the well known loop method of two-wire control and arranged to 95 rotate automatically to find an idle line in a group in case the call is for one line of a group of lines, and it is arranged to cooperate with the repeater and code selector shown in Fig. 2. 100

Fig. 2 shows the repeater R and the associated code selector CS individual to the line of substation B. The distributor D and the associated equipment are provided for plac-

ing the necessary codes on the bank of the code selector CS so as to secure the proper operation of the ringing relay 207. This ringing equipment is, of course, common to 5 all the repeaters and code selectors.

The line of substation A is assumed to be one line of a group belonging to the same subscriber, the connector C being arranged to complete a connection to the first line in 10 the group found to be idle. The line of substation B is a party line common to ten sub-stations. In the connector C, the first level has been reserved for party lines such as the line of substation B, it being assumed that 15 there are not more than ten such lines in the exchange. The first level springs associated with wiper 115 are arranged to operate only when the wipers have been raised opposite the first level. These springs may be operated 20 by a suitable cam arrangement on the shaft of the switch. The wiper 115 is shifted from the rotary test circuit to the impulse circuit when the wipers are opposite the first level so as to enable the wiper to 25 perform both functions assigned to it.

The apparatus having been described generally, a detailed description of its operation will now be given. For this purpose it will be assumed first that the connector C 30 is seized over conductors 110—112 in connection with a call to the group of lines containing the line of substation A. When the connector is seized by a selector switch, as is usually the case, conductor 111 is grounded 35 by the seizing switch, thereby making the connector busy to the other selectors having access to it. When conductor 111 is so grounded, a connection is closed through the off-normal contacts associated with the upper winding of the relay for the combined 40 ring-cut-off and change-over relay 105. Relay 105 operates and disconnects the associated impulse conductor from the rotary magnet and connects it instead to the vertical magnet, at the same time preparing a 45 locking circuit for itself. In response to the seizure of the connector, line relay 102 is operated over conductors 110 and 112, closing a circuit for release relay 103. Release relay 103 operates and prepares the 50 impulse circuit and opens a point in the release-magnet circuit. Relay 103 also places ground on conductor 111 so as to maintain the connection intact after the slow acting 55 release relay of the seizing selector has fallen back. Release relay 103 also places ground on the locking conductor 123.

When the calling subscriber dials the next digit 2 in the desired number, line relay 102 60 falls back twice momentarily, each time grounding impulse conductor 124 through an armature of release relay 102, and armature of busy relay 106, and series relay 107. Since conductor 124 is at this time 65 connected with the vertical magnet, the

vertical magnet is operated twice momentarily, raising the wipers 113—116 opposite the second level of bank contacts. Relay 108 is normally connected to the impulse conductor 124 so that it will operate quickly 70 when the first impulse is delivered. Relay 107 operates in series with the vertical magnet and connects relay 108 to ground, at the same time disconnecting it from the impulse conductor 124. Relays 107 and 108 remain 75 operated throughout the series of impulses. Relay 108, at its upper armature, completes the locking circuit of the upper winding of relay 105 to the grounded locking conductor 123, thereby maintaining relay 105 operated 80 after the off-normal springs have opened on the first vertical step of the switch.

At the end of the vertical movement, relay 107 falls back and opens the circuit of relay 108, whereupon relay 108 falls back 85 after a slight hesitation and opens the locking circuit of relay 105, the off-normal springs having previously opened. Relay 105 falls back and transfers conductor 124 90 from the vertical magnet to the rotary magnet.

When the next digit is dialled, relay 102 falls back a corresponding number of times, grounding conductor 124 each time it does so. As a result, the rotary magnet operates 95 and brings the wipers 113—116 into engagement with the desired contact set in the second level. Relays 107 and 108 are again operated in the above described manner. Relay 107 opens the connection between 100 stepping relay 104 and the rotary test wiper 115, and relay 108 closes a point in this connection. At its inner upper armature, relay 108 disconnects test wiper 114 from the test winding of switching relay 109 and connects it instead to busy relay 106, at the same time opening a point in the locking circuit of the busy relay. Relay 107 at its inner lower armature places a shunt 105 around the associated armature and contact of relay 106 so as to maintain the rotary-magnet circuit intact during the directed 110 rotary movement in case busy relay 106 should operate due to test wiper 114 passing over test contacts of busy lines. At 115 the end of the directed rotary movement, relay 107 falls back and busy relay 106 operates through test wiper 114 if the first line of the group is busy. Assume that the first line of the group is the line of substation A and that the line is busy. In this case, relay 107, upon falling back, completes 120 the connection between wiper 115 and stepping relay 104, whereupon relay 104 operates owing to the connection existing between the rotary test contact and the regular test contact through the jumper 117. Upon operating, relay 104 locks itself to the ground release trunk conductor 111 at 125 its upper armature through the interrupter 130

contacts of the rotary magnet. At its lower armature it places ground on impulse conductor 124 on the rotary-magnet side of series relay 107. The rotary magnet thereupon operates again and advances the wipers another step. A circuit is closed for relay 108 in multiple with the rotary magnet so as to maintain this relay operated during the automatic rotary movement of the connector. Relay 107 is not reoperated however, due to the point in the circuit at which the connection to the operating conductor is made. Near the end of the stroke of the rotary magnet, the interrupter springs are opened, whereupon stepping relay 104 falls back and opens the rotary magnet circuit. The rotary magnet again falls back and connects up the stepping relay again. If the second line in the group is busy, the stepping relay is again operated whereupon the wipers are advanced into engagement with the third line of the group. This rotary movement continues until an idle line is reached or until the last line of the group is reached. The last line of the group does not have a connection between the regular test and the rotary test contacts, with the result that the stepping relay cannot reoperate when this line is reached. In this case the rotary movement is stopped and relay 108 falls back and closes the locking circuit of busy relay 106, at the same time completing a connection from the busy-tone conductor to the lower talking conductor so as to enable the calling subscriber to hear the busy tone so that he will be reminded to replace the receiver and attempt the connection later.

Assuming now that the line of substation A is the first line in the group and that it is idle when called, busy relay 106 is not operated when the wipers land on the contacts of the line, in which case the deenergization of relay 107 is followed by the deenergization of relay 106. When relay 108 falls back, a connection is completed between release trunk conductor 111 and test wiper 114 through the test winding or relay 109 and contacts of relays 106 and 108. The circuit of this test winding is completed to battery through the cut-off relay of the line switch (not shown) over conductor 118. The cut-off relay and relay 109 operate in series. The cut-off relay clears the called line of its battery and ground connections. Relay 109 closes a locking circuit from conductor 123 to its own lower winding; places ground directly on test wiper 114; prepares a new locking circuit for ring-cut-off relay 105; opens the rotary-magnet circuit so as to prevent further rotation of the wipers of the switch; opens a point in the circuit of busy relay 106 so as to prevent a false operation of this relay upon the release of the connection; and at its upper and lower armatures

it connects up wipers 113 and 116 whereupon ringing current from the generator connected between the ringing lead and battery is projected out over the upper talking conductor, returning to ground over the lower talking conductor and contacts of relay 105 and 109.

When the called subscriber responds by removing his receiver, ring-cut-off relay 105 operates and completes a locking circuit for its upper winding through contacts of relay 109. At its upper and lower armatures, relay 105 disconnects the wipers from the source of ringing current and ground and connects them instead to the portion of the talking circuit having connected therewith the windings of back bridge relay 101. Back bridge relay 101 now operates over the called line and reverses the connections between the windings of line relay 102 and conductors 110 and 112, thereby reversing the direction of current flow in the conductors incoming to the connector for the purpose of giving supervision or operating a meter, or the like, depending of course upon the origin of the call. Relay 101 also opens a point in the circuit of the release magnet so as to prevent a premature release of the connector, and it places a multiple ground connection on the locking conductor 123 so as to prevent this conductor from being prematurely ungrounded.

The two subscribers may now converse with each other in the usual manner. When the conversation has terminated, they both replace their receivers. When the receiver is replaced at the called substation, in case this is done first, relay 101 falls back and prepares the release magnet circuit and reverses the current flow in conductors 110 and 112 to normal. When the calling subscriber hangs up under these circumstances, the deenergization of line relay 102 is followed by the deenergization of relay 103, whereupon the connection is released by the operation of the release magnet through an obvious circuit. In the interval required for relay 103 to fall back, relay 108 operates, but its operation is of no particular utility or consequence at this time. This relay falls back after relay 103 lets go. Relays 105 and 109 fall back responsive to the removal of ground potential from conductor 123.

Assuming now that the calling subscriber hangs up before the receiver is replaced at substation A, relay 101 is still operated when line relay 102 falls back. Relay 108 operates as before and opens the connection between the grounded test wiper 114 and release trunk conductor 111 (through the upper winding of relay 109 and contacts of relays 106 and 108) so as to permit the release of the connection to take place with the ground potential maintained on the test wiper 114 by relay 109. When relay 103 falls back, it

removes the ground potential from conductor 111 so as to enable the preceding switches to release. The release magnet is not operated because relay 101 is operated, and conductor 123 remains grounded for the same reason. Relay 108 falls back a moment after relay 103 falls back and removes ground from the operating conductor. Relay 108 closes the connection between the grounded test wiper 114 and release trunk conductor 111 so as to guard the connector against reseizure while it is being held by the nonreplacement of the receiver at substation A. The connection between wiper 114 and conductor 111, it will be noted includes the upper winding of relay 109. The resistance of this upper winding is sufficiently low to permit the guarding of the connector to be effectively accomplished.

When the subscriber at substation A replaces his receiver, relay 101 falls back and closes the release-magnet circuit, at the same time removing ground from conductor 123. The connector is restored to normal position in the usual manner and relays 105 and 109 fall back.

It will now be assumed that the connector C is seized in a call to substation B. When the connector is seized, it is prepared for operation in the usual manner and the vertical movement takes place in the hereinbefore described manner when the first digit 1 is dialled, the wipers 113—116 being at that time raised opposite the first level of bank contacts. The middle one of the first level springs associated with the rotary test wiper 115 is shifted to the left, disconnecting this wiper from the rotary test circuit and connecting it to a disconnected branch of the impulse conductor 124. When the next digit of the number is dialled, the rotary movement takes place in the hereinbefore described manner. The result is that wipers 113—116 are brought into engagement with the bank contacts terminating the conductors 119—122. If the line is busy when called, there is a ground potential on conductor 120, with the result that busy relay 106 is operated and it locks up when relays 107 and 108 have fallen back, giving the calling subscriber the busy tone. Assuming that the line is idle, the busy relay is not operated and switching relay 109 operates through its upper winding after relay 108 has fallen back, its circuit being completed to battery over conductor 120 through the cut-off relay of the associated line switch. A branch circuit to battery is completed through contacts of relays 203 and 201, Fig. 2, to battery through the winding of relay 203. Relay 203 operates at the same time that the cut-off relay of the associated line switch operates. At its lower armature, relay 203 opens a point in the self-restoring circuit of the code selector CS. At its upper armature, relay 203

locks itself to conductor 120, at the same time opening its initial circuit so as to prepare the self-busing circuit which comes into play upon the release of the repeater and code selector.

In the connector C, relay 109 operates and performs the hereinbefore described functions including the connecting up of the wipers 113 and 116. At its middle lower armature, relay 109 disconnects conductor 114 from the rotary magnet and extends it through the shifted first-level springs, wiper 115, and conductor 121 to the operating magnet of the code switch CS. Fig. 2, through contacts of relay 201 and the winding of the series relay 202.

When the calling subscriber dials the next and last digit in the number, a series of impulses is transmitted over conductor 114 of the connector C to the operating magnet of the code selector. The operating magnet responds to these impulses and advances the wipers 208 and 209 one step for each impulse, bringing wiper 209 into engagement with the bank contact terminating the correct ringing code conductor. The slow acting series relay 202 operates at the beginning of the impulsion and remains operated until the last impulse has terminated. When relay 202 falls back it completes a circuit for relay 201 through wiper 208 and the bank contact on which it is standing. Relay 201 operates and opens the impulse circuit; prepares the pick-up circuit; and places ground on the disconnected branch of conductor 120. As soon as the distributor D arrives in the pick-up position shown in the drawings, a circuit is closed for pick-up relay 204. Pick-up relay 204 operates, locking itself to conductor 210 and closing the connection between the ringing relay 207 and the code selector wiper 209. The code selected by wiper 209 is now impressed on ringing relay 207, which relay responds and signals the called station in accordance with his pre-assigned code.

When the subscriber at substation B responds by removing his receiver, the usual transmitter and receiver circuits are closed at the switch hook contacts, and ground is placed on both conductors of the called line through the lower switch hook contacts, the impulse springs of the calling device, and the ringer coils. When this occurs, answering relay 206 in the repeater R is operated with relay 207 in its normal position. Relay 206 operates relay 205. Relay 205 locks itself operated and opens the connection between relay 207 and wiper 209 so as to prevent further application of ringing current. Relay 206 also closes a bridge across conductors 119 and 122 through the left-hand repeating-coil windings so as to operate the ring-cut-off and back-bridge relays 105 and 101 of the connector D. It will be appar-

ent that the ringing current from the connector C is unable to reach the line of substation B prior to the operation of relay 206, and that such ringing current is immediately removed by the operation of the ring-cut-off relay 105.

The two subscribers may now converse with each other in the usual manner.

If the subscriber at substation B replaces his receiver first, answering relay 206 falls back and opens the bridge across the talking conductors at this point, resulting in the de-energization of back-bridge relay 101 of the connector C so as to permit the release of the connection as soon as the calling subscriber replaces his receiver.

However, if the calling subscriber replaces his receiver first, the connection is held up due to the continued energization of back-bridge relay 101 until the called subscriber replaces his receiver, at which time relay 206 falls back and permits the deenergization of back-bridge relay 101. When the connector C releases, it removes ground from conductor 120, permitting the cut-off relay of the associated line switch to release and permitting relay 203 of the repeater R to restore. When relay 203 restores, it disconnects itself from conductor 120 and connects conductor 120 to ground through the upper armature of relay 201, thereby replacing the busy condition on the conductor 120 so as to prevent the line from being seized again until the code selector has reached its normal position. At the lower armature of relay 203, the operating magnet of the code selector is connected to the grounded conductor 210 through its own interrupter contacts, with the result that the magnet is operated in a buzzer-like manner to advance the wipers 208 and 209 to their normal position. When wiper 208 reaches its normal position, it removes ground from conductor 210, stopping the operation of the operating magnet and deenergizing relays 201, 204, and 205.

Assuming now that the subscriber at substation B desires to originate a call, relay 206, operating as a line and impulse relay responds when the two conductors of the calling line are grounded at the lower switch hook contacts through the impulse springs of the calling device. At its upper armature, relay 206 completes a bridge across conductors 119 and 122, causing the associated line switch to operate in the usual manner to extend the connection to a first selector. When the calling subscriber operates his calling device, the circuit of relay 206 is interrupted a corresponding number of times, causing the automatic switches to operate over a loop circuit including conductors 119 and 122 in the same manner as when an ordinary common battery line is calling. There is an incidental operation of

relay 203 over conductor 120 at this time, but this is not of any particular utility. Relays 201, 202, 204, 205 and 207 do not operate when an outgoing call is made.

What is claimed is:

1. In a party-line automatic telephone system, switching mechanism controlled over a calling line to set up a connection to a party line, a station-selecting device individual to the selected party line, and means for operating said device from the calling line after the connection has been set up to the called line to signal any desired station on the party line. 70

2. In a party-line automatic telephone system, a plurality of party lines, means for setting up connections to any party line, and station selectors associated with said party lines all located at a common point and operable to select any desired called stations 85 after the connections have been set up to the lines. 80

3. In a party-line automatic telephone system, a connector switch operable over a calling line to set up a connection to a called 90 party line, a station selector associated with the called line, means including an operating magnet for operating said station selector to signal any desired called station on the line, and an impulse circuit for said magnet including a wiper of said connector. 95

4. In a combination party-line and non-party-line telephone system in which the non-party lines may be arranged in groups with a single line call number per group, a connector having access to groups of lines and having a rotary test wiper to enable it to rotate over busy lines to choose an idle line in a called group, a group of party lines terminating in the bank of said connector, 100 station selectors associated with said party lines, an impulse circuit for any selected stations selector including an impulse conductor in said connector and a branch impulse conductor individual to the station selector, 110 and a shifting device in said connector operated when a party line is called to shift said rotary test wiper from the rotary test circuit into connection with said impulse conductor to complete the impulse circuit to the 115 selected station selector. 105

5. In a telephone system, a rotary connector having a regular test wiper and a rotary test wiper, an impulse conductor in said connector over which the magnets of 120 said connector are operated, and contacts operated only in case certain lines are called for shifting the rotary test wiper from the rotary test conductor to said impulse conductor. 125

6. In combination with a party line, a combined code selector and impulse repeater individual thereto, said code selector being arranged to select the correct ringing code when the line is called, and the repeater be- 130

ing arranged to repeat switch operating impulses to the central office apparatus when the line is calling.

7. In a party line telephone system, a party selector individual to a party line, means for extending a connection to said line and for subsequently operating said selector to select the desired called party on the line, means included in the connecting 10 means for maintaining the called line busy to other connecting means until the connection is released, means for releasing said code selector responsive to a breaking down of the established connection with a line, and 15 means in the code selector for replacing the busy condition on the line and for maintaining it until the code selector is released.

8. In a telephone system, a plurality of party lines, each line having a directly operated device individual thereto for signalling any desired station thereon, directly operated switching means for selecting any desired line, and means for transmitting digit impulses from said switching 25 means to the device of a selected line for operating the device.

9. In a telephone system, a rotary connector having directive and automatic rotary movement, a wiper for controlling the 30 automatic rotary movement, and means for transmitting digit impulses over said wiper.

10. In a telephone system, a party line, means individual to the party line controlled by digit impulses to signal a desired station 35 on the line, a connector having access to said line, said connector having a pair of talking conductors terminating in wipers, a special wiper, and circuit arrangement for transmitting digit impulses from the connector 40 over said special wiper to said first-mentioned means.

11. In a telephone system, a party line, means individual to the party line controlled by digit impulses for signalling any desired 45 station on said party line, a connector having access to said party line, and means in the

connector for transmitting digit impulses to said first-named means for operating the same to select a desired station on the party line.

12. In a party line telephone system, a party selecting device individual to a party line, means for extending a connection from a calling line to said party line and for subsequently operating said selecting device to 55 signal the desired called party on the line, means for maintaining the called line busy to other connecting means until said selecting device is released, and circuit connections effective responsive to the termination 60 of the conversation by both of the conversing parties for releasing said selecting device.

13. In a rotary connector switch, a stepping relay for controlling the automatic 65 trunk hunting movement of the switch, a test wiper, contacts controlled by the switch shaft responsive to a predetermined movement of the shaft, circuit connections controlled by said contacts in one position for controlling 70 the stepping relay, and circuit connections controlled by said contacts in another position for establishing a digit impulsing circuit to said wiper.

14. In a telephone system, a switch having 75 access to lines extending to subscribers that have a plurality of lines as well as to lines that have a plurality of subscribers thereon, all lines terminating in the same number of contacts at the switch, means responsive to 80 the selection of a line of the first-mentioned kind by the switch for causing the switch to hunt for and seize an idle one of the lines extending to the desired subscriber, and means individual to each party line effective 85 if a party line is selected for selectively signalling any desired party on the line.

In witness whereof, I hereunto subscribe my name this twenty-ninth day of March, A. D., 1927.

NORMAN H. SAUNDERS.
